CARL A. ANDERSON, OF NORTH BRADDOCK, PENNSYLVANIA.

AUTOMATIC FIRE ALARM.

1,405,251.

Specification of Letters Patent. Patented Jan. 31, 1922.

Application filed May 18, 1920. Serial No. 382,438.

To all whom it may concern:

Be it known that I, CARL A. ANDERSON, a citizen of the United States, and a resident of North Braddock, in the county of Allegheny and State of Pennsylvania, have invented a new and Improved Automatic Fire Alarm, of which the following is a full, clear, and exact description.

This invention relates to an automatic fire alarm. The object of the invention is to provide a device which is adapted to be moved around from place to place, as at various locations within a house or enclosure used as a residence; and may be employed in a factory or mercantile establishment and shifted from one place to another which for the time being seems to be a special source of danger.

The initiating cause of the alarm is a form 20 of thermostat, and consists of metal plates constructed and adapted to be warped or deformed from a normal arrangement by a rise in temperature. This initiating cause of the alarm is small, light, portable, and 25 controls a purely mechanical alarm in close proximity, and also controls an electric circuit in which an electromagnetic alarm is included and is preferably situated at a central point or station, either in the same building or at a distance from it at a central 30 station.

The drawings illustrate the invention.

Figure 1 is a top plan view;

Figure 2 is a side elevation of the same; 35 and

Figure 3 is a detail.

There is a base plate of sheet steel 5 which is provided with a flange 6 on each edge, and flange pieces 7 of sheet metal are bolted 40 across the ends to serve as legs. The object in providing these flanges is to stiffen the structure. Fixed to the underside of this base plate 5 is a sheet zinc plate 10 having flanges 11 on its opposite edges, and these 45 flanges are cut away at 12, that is, a point near the center, and there is a space 13 at each end as well as at the center. This zinc is sensitive to variations in temperature, and a rise in temperature in the atmosphere of the 50 room, or from a fire that may be started in the vicinity, will cause the sheet zinc to twist or buckle, and the sheet steel will either buckle or twist to a greater or lesser extent. Located on top of the sheet base plate 5 is 55 a mechanical motor 15 which has a form of clockwork having sheet-metal plates 16 bolt-

ed together by screws 17 to form bearings for arbors 18, 19, 20 and 21, as shown in Figures 1 and 2. Fastened on top of the base 5 is a gong 22, or an alarm bell, the 60 hammer 23 of which is supported on the arbor 20. There is a spiral clock spring in a spring case 24 which is wound by a fixed key 25 on the arbor 18, and there is an escapement which terminates in an escapement 65 anchor 26. This escapement anchor 26 oscillates and is actuated by an escapement wheel 27. The oscillation of this escapement wheel 27 vibrates the bell hammer 23 and produces an audible response on the gong 22. Normally a stop 28 projects into the path of an arm 29 fixed on the arbor 20 and holds the 70 spring motor at rest. Upon the application of heat, the zinc plate 10 is deflected and withdraws a stop 30, allowing the stop 28 to 75 fall or move out of the path of the arm 29, which releases the arbor 20 and the bell ringing immediately starts. This gives an audible alarm anywhere within audible distance of the location of the device. 80

For the purpose of giving an alarm at a more remote point, there is provided an electromagnetic alarm 40. I prefer to use a vibrating electric bell, and I provide an electric circuit 41 with a battery 42, and the 85 magnet of the vibrator bell 40 connected with screw posts 43 and 44 on the metal base piece 5. Connected to the screw post 43 are contact springs 45, and connected to the screw post 44 is a contact spring 46. 90 This contact 46 is supported on the arm 47 pivoted at 48. A spring 49 engages a projection 52 on the arm 47 and tends to force the contact 46 on the arm 47 into engagement with the contact 45. This closes the 95 circuit 41-42 and the contacts 45 and 46 are closed. On the pivoted arm 47 is a flat spring 50 the free end of which slides along the top of the base 5; and the stop 51 which projects on the upper surface of the base 100 plate 5, as seen in Figures 2 and 3, is normally in the path of movement of the spring 50. When a rise in temperature, due to fire, buckles the plate 10, the stop 51 is moved out of the path of movement of the end 105 of the spring 50, the electric contact 46 engages with the electric contact 45, and the circuit 41-42 is closed and an alarm sounded on the electromagnetic alarm 40. It is to be noticed that a rise in temperature 110 due to an incipient fire has, therefore, started the mechanical motor to sound an alarm on

the gong 22 and has released the arm 47 which, in response to the action of the spring 49, has closed the contacts 45 and 46, thus closing the alarm circuit 41 and sounding an alarm on the bell 40 located at a distant point.

What I claim is:

1. In an automatic fire alarm, an apertured base plate, a metal plate secured to the base plate and adapted to buckle or warp upon a rise in temperature, a motor driven audible alarm mounted on the base plate, means for holding the motor in check and including a movable member, and a member carried by the second plate and extending through the aperture of said second plate and normally engaging the movable member of the checking means to hold it in operative position whereby when the said plate buckles upon a rise of temperature its member will be withdrawn from the movable member of the checking means to release the same.
2. In an automatic fire alarm, an apertured

metal base plate, a second metal plate secured to the under side of the base plate 25 and adapted to buckle upon a rise of temperature, a motor driven audible alarm on the base plate, a movable member coacting with a member of the motor to check the same, and a member carried by the second 30 plate and extending through the aperture of the base plate and engaging the said movable member.

3. In an automatic fire alarm, an apertured metal base plate, a flanged zinc plate secured to the under side of the base plate and provided with a member projecting through the aperture of the base plate, a motor on the base plate, a gong on the base plate, a hammer operated by the motor, an arm on an arbor of the motor, and a movable stop engaging the member of the zinc plate and held thereby in engagement with the arm of the motor to hold the said motor at rest.

CARL A. ANDERSON.
